(57) **CLAIM**

The ornamental design for a tow truck body, as shown and described.

DESCRIPTION

FIG. 1 is a rear perspective view showing my new design.

FIG. 2 is a rear elevation view of FIG. 1.

FIG. 3 is a front elevation view of FIG. 1.

FIG. 4 is a left side elevation view of FIG. 1.

FIG. 5 is a right side elevation view of FIG. 1.

FIG. 6 is a top plan view of FIG. 1 in a closed position.

FIG. 7 is a bottom plan view of FIG. 1 in a closed position.

FIG. 8 is a rear perspective view of FIG. 1 in a open position.

FIG. 9 is a rear elevation view of FIG. 1 in a open position.

FIG. 10 is a front elevation view of FIG. 1 in a open position.

FIG. 11 is a left side view of FIG. 1 in a open position.

FIG. 12 is a right side elevation view of FIG. 1 in a open position.

FIG. 13 is a top plan view of FIG. 1 in a open position.

FIG. 14 is a bottom plan view of FIG. 1 in a open position.

FIG. 15 is a exploded rear perspective view of FIG. 1 in a closed position; and,

FIG. 16 is a rear perspective view of FIG. 1 in a closed position.

In the drawings, the broken line in FIG. 16 depicts environmental subject matter and forms no part of the claim.
